UNITED STATES PATENT OFFICE.

HENRY W. ADAMS, OF PHILADELPHIA, PENNSYLVANIA.

IMPROVEMENT IN BRICK-KILNS.

Specification forming part of Letters Patent No. 80,046, dated July 21, 1868.

To all whom it may concern:

Be it known that I, HENRY W. ADAMS of the city and county of Philadelphia, and State of Pennsylvania, have invented a new and useful Improvement in Brick-Kilns; and I do hereby declare that the following is a full, clear, and exact description of the construction and operation of the same, reference being had to the annexed drawings, making a part of this specification, in which—

Figure 1 represents a perspective view of a kiln about fifteen feet wide, and thirty-two feet long, and twelve feet high, more or less. Other dimensions may be used, if deemed preferable.

Letter A represents one side of the kiln. L indicates an opening into the kiln for filling and emptying it. M shows the fire-tile over the whole length of the fire-flues, to prevent the fire from striking directly against the unburnt brick, and over-burning them. K K represent fire-brick set up on their edges, and distant from each other the thickness of one brick, so as to form parallel flues all over the floor of the kiln, and under the entire bottom of the unburnt bricks when set in the kiln. They are set about flush with the fire-places, and on them rest the fire-tiles which cover the flues, so as to divide and distribute the heat equally over the entire bottom of the kiln. N represents the arch, resting on the two opposite sides and ends of the kiln, to prevent the heat from evaporating from the open top, as is now the case, and also to enable me to employ a draft on the top to lift up through the mass of burning bricks the superheated gases and aqueous vapor supplied to the over-heated flues from without, as well as the heat set free from the burning fuel. The arch is pierced with eight holes, equally distant from each other. The inside of the kiln being about ten or twelve feet wide, and twenty-five or thirty feet long, more or less, these draft-holes should be thus separated from each other, so as to cause the heated gases and vapors to ascend perpendicularly and equally through the kiln, and not draw to a center on the top, and leave the sides and top of the burning bricks imperfectly calcined. O¹ O¹ represent two joints of stove-pipe or their equivalents, fitting into and extending through the arch. For a kiln about the size of the one now described these pipes should be about five inches in diameter. A cross-pipe unites

them. The same arrangement is made on the opposite side of the arch. The pipes O¹ O¹ unite the last-mentioned pipes at their middle points with similar ones on the opposite side of the arch, and should be about seven inches in diameter, so as to receive the contents of O² O². Then O¹ O¹ are united by O³, at the center of which, and looking upward, is attached a ten-inch pipe, O, which will carry off and discharge into the air, or elsewhere, the smoke and heated products of combustion, drawing alike from all parts of the kiln. To increase the draft of the kiln a jet of steam is let into the pipe O through the pipe p, which shoots up through O, draws air through the flues, and lifts up the movable steam and heat through the kiln, and renders the upper portions sufficiently hot by robbing the bottom and lower parts of their excess of caloric. V represents a peep-hole, through which to look in to see when the top of the kiln becomes red hot. R S T T show the arrangement of steam-pipes for conveying steam from a boiler and injecting it into the flues above the coal or fuel, to be superheated by contact with the hot sides and top of the said flues, and drawn up through the interstitial spaces of the kiln, carrying the excess of heat from the bottom to the top of the same. These steam-pipes lie in cold-air flues parallel to the fire-flues, and extend through their entire length. Their opposite ends are plugged up, and their sides, next to the fires, are pierced with fine holes about two feet apart, from which fine jets of steam escape, through small draft-holes, into the fire-places.

The object of this is to enable me to remove, at pleasure, the superabundant heat which accumulates in the bottom of the kiln, and damages the lower courses of the burning bricks, to the upper portions, where it is needed to bring the upper courses to the desired cherry-red heat. The amount of steam thus employed is regulated by a stop-cock, and depends on the redundancy of heat which the base of the kiln may, from time to time, acquire.

Fig. 2 shows a section of the kiln cut off, exposing to view its interior, as shown at B, and uncovering the fire-flues C C, the cold-air flues H H D D, the ash-pits C' C', the openings from the air-flues into the fire-places G G F F, the steam-pipes E E, the grate-bars, and the fire-tiles M M, covering the fire-places and

resting on the fire-bricks K K K, turned up edgewise, and separated from each other by a space equal to their thickness, for forming cross-flues to distribute and circulate the heat uniformly under the whole kiln. A and L represent the thickness of the walls, and N shows the arch resting upon them. In a kiln ten feet wide on its inside and thirty feet long the fire-places are about sixteen inches square, the ash-pits C' C' the same, the air-flues H H D D eight inches square, the number of openings G G F F fourteen, and each two inches square, more or less. The steam-pipes are pierced with an equal number of fine holes directly opposite to these openings, so as to shoot jets of steam through them into the fire-places just above the burning fuel.

Fig. 3 shows the method of constructing the floor of the kiln, on which the bricks to be burned are set. C' represents the grate-bars. The sides of the fire-places are lined with fire-brick, and the walls are built up sixteen inches, more or less. On the bricks, turned up on their edges k k k, and leaving spaces j between them, the fire-tile M rests, covering the fire-places, and compelling the escaping heat to diverge sidewise, enter the numerous narrow spaces, and distribute itself over the entire bottom, and thus ascend equally through the kiln. The object is to protect the lower courses of bricks from the destructive action of an intense fire playing directly upon them. The present method is to form the walls of the fire-places with the unburnt bricks, and to arch them over with the same. The consequence is, that several of the lower courses are melted, twisted, and depreciated in value by this excessive heat. By the present method, also, the entire top of the kiln is open to the air. The heat, being unconfined, escapes into the air, and fails to burn the top courses sufficiently to render them hard and turn them to a deep-red color. The want of an adequate artificial draft causes a deficiency of hot gases to ascend upward and heat the top, and especially when anthracite coal is used, and in damp and rainy weather. The deprivation of the white-hot flues of steam, to absorb their excessive ardor, and lift it up into the higher and less calcined parts of the kiln, necessarily permits too much heat to accumulate at the bottom and too little to rise to the top.

The want of uniformity in burning a kiln is the most damaging drawback to the brick-maker. While human ingenuity has been taxed to its utmost for many years to devise and perfect machines for molding and pressing bricks, very little attention has been paid to burning them in a more skillful and profitable manner.

The general testimony of brick-makers, obtained by recent inquiries, is, that the first quarter of a fresh-burnt kiln, taken from the top, is composed of soft brick, not sufficiently burned, easily broken, and crumbling to powder by the action of the elements. In a kiln of two hundred thousand, the first fifty thou-

sand are worth at this time, in this vicinity, seven dollars per thousand. The second quarter is valued at twelve dollars per thousand; the third at thirty-five, and the fourth is seriously damaged by being too much burned, and varies in value. From this it appears that the first quarter is worth three hundred and fifty dollars; the second quarter, six hundred; the third, seventeen hundred and fifty, and the fourth much depreciated. It further results that if the first quarter could be burned as well as the second, a profit of two hundred and fifty dollars would be saved to the manufacturer; and if the first could be burned as well as the third, a further profit would accrue of fourteen hundred dollars; and if the second were burned as perfectly as the third, a still additional saving would be realized of eleven hundred and fifty dollars. If, then, the first three quarters could be burned alike, a clear advance of twenty-five hundred and fifty dollars would be made by the manufacturer. Besides, if the last quarter could be as perfectly burned, at least five hundred dollars more would be gained.

From these well-ascertained results, every kiln of two hundred thousand bricks would be worth three thousand dollars more, if properly and equally burned, than it is now. This amount would be over three times as great if pressed brick could thus be uniformly burned. A great opportunity for the improvement of the present unskillful and unscientific mode of brick-burning obviously exists.

To contribute something toward this important improvement has been my object in devising a new and better plan. I have shown one mode of constructing my kiln. I do not confine myself to this method. Many others may be substituted. It may be circular, with a circular arch. It may be dug in the ground and the arch rest on the sides of the pit, where sloping elevations are convenient. The arch may be covered with earth or sand to protect and seal it more perfectly. But the life of my invention consists in a new method of producing, distributing, transporting, and retaining the necessary heat in all parts of the kiln, so as neither to overburn the bottom nor underburn the top, but to equalize the heat of both by means of a positive, reliable, and instantaneous power to supply any desirable degree of heat to all parts of the kiln alike. This I accomplish by the combination of a covered, air-tight kiln with a powerful draft, procured by a jet of steam, as represented, arranged to draw alike from all parts of the kiln, as indicated by my draft-pipes, and yet under the control of a stop-cock, together with the accurate and positive manner of introducing large or small quantities of air and steam into the fire-places, one or both, or neither—the former to promote perfect combustion, and the latter to become superheated at the expense of the overheated fire-places and bottom bricks, and both to carry up more caloric to be distributed and

utilized in bringing the topmost courses to a cherry-red heat. These combined means hold indispensable relations to each other.

An arched or covered kiln, without a sharp and controllable steam-jet to produce just such a draft as may from time to time be wanted, would be worse than none. A draft such as this could not be had without a covered kiln, and neither would be useful without a supply of air to the large air-flues to rush through the openings into the fire-places, like streams from a bellows, when the draft is strong on the top; and this air again would produce such intense heat as to puddle down the lower part of the kiln, unless I had the ready means of tempering the heat by letting in steam to transport it to the top and distribute it through all the interstices of the kiln.

By shutting off the steam from the flues, opening the doors of the large air-passages, increasing the draft on the top, by letting on more steam, and supplying more fuel to the fire, the heat is suddenly increased at the bottom.

By letting on steam into the fire-places when the bottom is thus overheated, and closing the doors to the air-passages, the lower part is cooled and the upper part rendered hotter. In fact the heat is under perfect control, and it is only necessary to have a little experience in regulating it to burn a kiln of bricks without burning them too much or too little.

Much time is also saved in burning brick upon my plan. In the first place, having the command of a powerful draft, always reliable, irrespective of weather, I can heat up the kiln much quicker than by the old process. In the next place, I can burn it through at the top much sooner, without being obliged to fire so hard and so long as to damage the bottom in order to half-burn the top. In addition I can save considerable coal. I can send my waste heat from the draft-pipe *o* under the boiler to make my steam. I can hold the red heat in the kiln much longer than in the present uncovered kilns. When the top of the kiln is at a cherry-red heat, and has remained so a day or more, by stopping the draft on the top, adding only a small quantity of fuel, shutting up the doors of the air-passages, and finally closing up all the doors tight, the heat will remain hot enough to complete the burning without any more fuel. Another advantage is, that I can cool down my kiln, so as to empty it, in much less time than it requires to cool the present kilns. By opening the doors of the air-flues and letting on the draft on the top, so as to draw cold air up through the kiln and carry the heat out of the top, the process of tempering down goes on rapidly and safely. The cold air first passes into the fire-flues and becomes heated before it comes in contact with the bricks, and so carries up caloric to the top and gradually discharges it into the air. Hence the top of the kiln will remain hottest to the last.

My method of burning brick and other materials composed of clay can be applied equally as well by setting the brick so as to build the fire and air flues at one end of the kiln, and draw the hot products of combustion and superheated steam horizontally through the whole kiln by means of the steam-draft at the other end of the kiln. In this case the kiln would be longer than its height, and the top would be covered by any method best adapted to render the kiln air-tight. Another benefit of my kiln is, that green or undried brick can be set up directly in it and dried prior to burning by drawing air through the mass by means of the steam-draft, substantially as shown and described. This saves the time and expense of handling and drying the undried brick before setting them in the kiln.

Having given a full, clear, and exact description of the construction and operation of my improved kiln, what I claim, and desire to secure by Letters Patent, is—

1. The peculiar arrangement of the numerous and narrow heat-distributing flues *y* at right angles to and in combination with the covered fire-places *C C*, for receiving, dividing, and conveying their heat underneath the entire bottom of the bricks when set in the kiln to be burned, substantially as described.

2. The air-flues *H H D D*, in combination with the openings *G G F F* into the fire-places *C C*, substantially in the manner and for the purposes set forth.

3. The steam-pipes *R S T T* in Fig. 1, and passages *F F* and flues *E E* in Fig. 2, in combination with the fire-places *C C*, for the objects indicated, and substantially in the manner shown.

4. The arrangement of the pipes *p, O² O², O¹, O³, and O*, in combination with a covered brick-kiln, for exhausting the smoke and gaseous products of combustion and superheated steam in an equal and uniform method from all parts of the kiln, for the objects described, and substantially as represented.

5. The use of a jet of steam to create a draft at the top or end of the brick-kiln, substantially as shown, and for the ends proposed.

6. The combination and arrangement of the exhaust-pipe *O*, when supplied with a jet of steam, with the fire-places *C C*, and with the air-flues *H H D D*, and with the openings *G G F F*, and with the steam-pipes *E E* in Fig. 2, when they severally supply those vehicles of heat to the bottom of the kiln, which the steam-jet issuing from *O* pumps from its top, as herein substantially shown and described.

7. The construction and operation of the brick-kiln, substantially as shown and explained, and for the purposes set forth.

HENRY W. ADAMS.
